UNITED STATES PATENT OFFICE.

BENJAMIN F. MERRITT, OF EAST ORANGE, NEW JERSEY, ASSIGNOR TO WESTERN ELECTRIC COMPANY, OF NEW YORK, N. Y., A CORPORATION OF ILLINOIS.

SELECTING MECHANISM.

1,161,500.

Specification of Letters Patent. Patented Nov. 23, 1915.

Application filed January 24, 1914. Serial No. 814,258.

To all whom it may concern:

Be it known that I, BENJAMIN F. MERRITT, a citizen of the United States, residing at East Orange, in the county of Essex and 5 State of New Jersey, have invented a certain new and useful Improvement in Selecting Mechanism, of which the following is a full, clear, concise, and exact description.

This invention relates to selecting mechanism and more particularly to selecting mechanism of the manually controlled type adapted for use in perforating and circuit selecting apparatus.

The object of this invention is to provide 15 a selecting mechanism of the above type which is simple in construction and reliable and efficient in operation, and in which the pivoted connections are reduced to a minimum.

20 To the above ends manually actuated devices are provided which coöperate with slidable selectable members adapted to be moved on a diagonal from their normal position of rest, whereby mechanisms are positioned to perform the desired selecting operations.

The above and other objects of this invention will be fully set forth in the following description and claims, and will be more 30 readily understood by reference to the accompanying drawing in which—

Figure 1 shows a plan view of a keyboard perforator, part of the inclosing case and frame being broken away to more clearly 35 show the mechanism; Fig. 2 is a sectional view along the line 2—2 of Fig. 1; and Fig. 3 shows a partial section of the arrangement of parts for selectively actuating circuit connections or contacts.

40 In the illustrated embodiment of the invention, the manually actuated devices comprise a keyboard arranged like the keyboard of an ordinary typewriter, each key being capable of independently performing the selecting operations required to produce the proper arrangement of perforations in the transmitting tape or selectively actuate circuit controlling mechanism. Each key lever 5 is pivoted to the frame 6 and is provided with a spring normally elevating the outer end thereof. The springs and pivots are not shown as the method of their employment is well known. Each key lever has thereon a characteristic arrangement of

55 downwardly projecting lugs 10 differing from that of every other key lever. The arrangement of these lugs determines the combination of perforations representing each character or key.

60 Situated directly beneath and extending in a direction transverse to the key levers 5, are five slidable selectable members 11 and a similar circuit controlling member 12. The frame 6 is provided with a number of pedestals 15, 16, 17 and 18 which serve to support 65 and guide the members 11 and 12. A roller 20 is located between pedestals 15 and 16 and a roller 21 is located between pedestals 17 and 18. Likewise, situated between and secured to the pedestals 15, 16 and 17, 18, 70 are guiding combs and upper and lower stops 23 and 24 which insure the proper position and alinement of the slidable members. Each selectable member 11 and the circuit controlling member 12 are provided 75 with inclined plane portions 25, 26 at one end, and 27, 28 at the other end, between which the rollers 20 and 21 are respectively situated. Each member is likewise provided with a spring 30. Normally, the springs 30, 80 exerting force from right to left as viewed in Fig. 2, cause all the members 11 and 12 to be elevated against the upper ends of stops 23 and 24. When, however, a key lever 5 is depressed, certain of the selectable members 11 and in every instance the contact controlling member 12 will be depressed by the lugs 10 against the tension of the springs 30 and, because of the inclined planes 26 and 28 bearing on the rollers 20 and 21 respectively, 85 90 will also move in a lateral direction along a line diagonal to the normal position. The resultant motion therefore is along a diagonal to their normal position of rest. The contact controlling member 12 is operated 95 by every key for a purpose to be presently described. The extent of downward and lateral motion of the slidable members is controlled by the lower ends of stops 23 and 24.

100 The selectable members 11 are provided with projecting lugs 35 each equipped with a socket 36. Into this socket is fitted the rounded end of a lever 37 pivoted to the frame at 38. This socket construction is to 105 facilitate the assembling and removal of the parts. The levers 37 carry arms 39 pivoted thereto at 40. It will be readily observed,

therefore, that any downward movement of a key lever 5 causes the lateral movement of certain of the arms 39.

The arms or punch actuators 39 are adapted to be interposed between a common hammer or power member 41 and the selected members or punches 42 when they are in their advanced position, but to normally assume a position out from between the hammer and punches, as shown in Fig. 2. Each punch 42 is slideable in a punch block 44 and co-operates with a die block 45 to punch the holes in a tape 46. A spring 48, secured at one end to the punch block 44, passes through a small opening in its corresponding punch 42 and normally rests against a stop 49. When, however, any punch 42 is elevated by the hammer 41, the end of the corresponding spring 48 is raised from the stop 49, whereby energy is stored in the spring to withdraw the punch 42 from the paper upon the retraction of hammer 41. One punch 50 is longer than the rest and is actuated at the depression of each key. This 25 is the feed hole punch and is for the purpose of punching the holes for the feed wheel to be hereinafter described. It is equipped with a spring 48 the same as the other punches.

30 Hammer 41 is mounted upon the end of an arm 55 secured to shaft 56 which is rotated by a magnet 57 through a coupling 58. Magnet 57 is in a circuit normally open at contact springs 60 and 61. Springs 60 and 35 61 are adapted, however, to be closed by the upwardly extending lug 63 of the contact controlling member 12 after all of the desired arms 39 have been advanced to a position between their corresponding punches 42 and the hammer 41. Upon the depression of each key, therefore, the member 12 causes the closing of the energizing circuit for the magnet 57.

To provide for the advancement of the 45 tape, the shaft 56 is provided with an arm 65 carrying at its outer end a spring-tensioned pawl 66. Pawl 66 is adapted to engage the teeth of, and rotate a star wheel 67, upon the retraction of the armature of 50 magnet 57. The teeth of the star wheel 67 engage the openings created by the feed hole punch 50 and consequently, when the depressed key lever 5 is released, a clean surface of paper is thereupon presented for 55 the next selection.

When embodied in a keyboard circuit controlling device, the die block 45 is dispensed with. In its place sets of springs 70, 71 (Fig. 3) are substituted, which are 60 normally separated but adapted to be selectively closed through the agency of pins

72 which take the place of the punches 42. There is one set of contacts 70, 71 for each pin 72. The pins 72 are under tension of springs 48 and are arranged to be moved 65 against that tension when desired by means of a hammer 41 secured to shaft 56 by arm 55 and actuators or arms 39, precisely as in the perforator above described. In the circuit controller there is no necessity for a 70 long pin actuated upon each depression of a key like the feed hole punch 50 of the perforator and consequently it may be dispensed with.

What I claim is:

1. A selecting mechanism comprising a plurality of manually actuated devices, a plurality of members selectively movable by said devices in predetermined groups along paths diagonal to their normal position, and means controlled by said members.

2. A selecting mechanism comprising a plurality of manually actuated devices, a plurality of members to be selected, a plurality of slideable selectable members equal 85 in number to said members to be selected, said selectable members being adapted to be moved along a path diagonally disposed to their normal position, means associated with said manually actuated devices for selectively operating said slideable members in predetermined groups, and means for actuating the members already selected by said manually actuated devices.

3. A keyboard selecting mechanism comprising a plurality of selectable members capable of being moved along paths diagonal to their normal positions, a plurality of key levers adapted to selectively move said selectable members in various combinations, 100 operating means controlled by said members, and a power mechanism cooperating with said members and said means to effect the operation of said operating means.

4. A selecting mechanism comprising a 105 plurality of reciprocating actuators, a plurality of manually actuated devices, a plurality of members selectively movable by said devices in predetermined groups along paths diagonal to their normal position, and means cooperating with said actuators and said members for converting the diagonal movement of said members into a reciprocating movement of said actuators.

In witness whereof, I hereunto subscribe 115 my name this 23d day of January, A. D. 1914.

BENJAMIN F. MERRITT.
